UNITED STATES PATENT OFFICE.

ADOLPH L. FRIEDENTHAL, OF PORTLAND, OREGON.

SPAT.

Application filed March 8, 1926. Serial No. 93,076.

The present invention relates to an article of apparel generally termed a "spat", and it has to do with the manner in which the article is shaped and constructed. The configuration of the article is one of an improved character, and hence, it is upon this improvement particularly that patent protection is sought.

Among the objects of the invention are included the following:

A new style of spat adapted to prevent "pulling up" at the toe and heel;

An improved pattern for a spat whereby it may be made to conform to the shape of the foot and provide a snug fit thereover;

A new style for a spat whereby it affords additional protection to the foot and assists in protecting the hose rather than putting more wear thereon as is now the general case with conventional spats; and

The provision of a neater and more completely protective spat for general wear, and having the advantages of being readily placed in position upon the foot and easily removed therefrom.

These objects, and such other objects as may hereinafter appear, are obtained by the novel construction of the spat, the combination of the elements thereof, and the arrangement of its parts, all of which are illustrated in the accompanying drawing and herein-after fully described.

Three forms of spats illustrative of the invention are disclosed in the accompanying drawing, hereby made a part of this application, and in which

Figure 1 is a side elevation of one form of the invention;

Figure 2 is a back elevation of the form of the invention shown in Figure 1, the spat being folded upon itself in a plane perpendicular to that shown in Figure 1;

Figure 3 is a fragmentary side elevation of a modified form of spat; and

Figure 4 is a similar view of another modified form of the invention.

Like reference characters are used to designate similar parts in the drawing and in the description which follows.

Figures 1 and 2 should be first examined, and the form of device therein disclosed described. The spat therein illustrated is designated 10, and comprises a leg portion 11 with a turned over top section 12, the leg portion 11 being of vertically ribbed mate-

rial. In its upper structure, it is not unlike heavy woolen short hose as is disclosed in Figures 1 and 2.

At the front of the spat 10 is an instep covering portion 13 terminating in a tip 14. The portion 13 has an edge 15 which at first is almost parallel to the ribs in the leg portion 11 but as the lowermost part thereof is reached, it curves abruptly to follow the contour of the rounded tip 14. The portion 13, at its top or beginning, comprises more than half of the circumference of the spat 10 while at the tip 14, part 13 does not exceed approximately one-third of the circumference of the body 10.

The heel portion of the garment 10 is designated 16 and this portion extends downwardly but a short distance in comparison with the long front 13. Said part 16 terminates in a less pronounced tip 17 and its edge 18 is generally obliquely angular to the ribs in leg portion 10. The toe and heel sections, 13 and 16, are separated by an undercut portion 19, at which part an elastic strap 20 intended to pass under the foot is attached.

For preventing ravelling or possible damage to the raw edge of the material of the spat 10 at sections 13 and 16, a stitching 21 is provided, and this stitching is generally continuous about the bottom of the spat. It is an elastic stitching and gives to the garment a fine finish and the appearance of a workmanlike article.

When a spat of this type is slipped onto the foot, it depends well down over the instep and the heel. Part 13 covers the instep snugly and to such an extent that the shoe (if it be worn outside as is usual and is a low shoe) has no tendency to force the material of spat 10 upwardly. At the heel the same condition exists, and the part 16 completely protects the wearer and avoids the tendency of the shoe to work under the spat 10 and force the material thereof upwardly.

The elastic ribbing in body 10, of course, furnishes sufficient elasticity to compensate for wear and for the differences in ankle size resulting from the flexing movement thereof. The garment may be readily removed by pulling off much after the fashion of short hose.

In Figure 3, a second form 10^a of the invention is shown. The leg portion is designated 11^a, and the top is not shown. In-

stead of a marked depending instep and heel portion, the bottom 25 of this garment is slightly rounded, and is provided with an elastic 26 at an angle to the ribbing of body 5 10^a. The front 13^a is at its tip 14^a quite like the front 13 and tip 14 of Figures 1 and 2. This garment does not fit quite so snugly about the foot as the form shown in Figures 1 and 2 and hence is not equally protective. It is preferably finished at its edge by a stitching 21^a of the characters previously described.

In Figure 4, another form of spat is shown. The spat is designated 10^b, and has 15 a leg portion 11^b which, instead of being cylindrical, is cut to provide a forwardly projecting instep portion 13^b terminating in a slightly upturned tip 14^b. A seam 28 joins the material of the garment at the 20 front of leg section 11^b. The bottom edge 15^a of this type of garment is almost directly transverse of the ribs of the body 11^b, but this edge may turn up slightly at the back 16^b. An edging 21^b extends from 25 front to back on both sides of the body 11^b.

This last described garment is intended more for larger sizes and where a very snug fit about the foot is desired without dependence upon the elasticity of the ribbing 30 of body 11^b. An elastic band 20^b may be disposed at a convenient point intermediate

13^b and 16^b to pass under the foot and hold the garment in place.

What I claim as new is:—

1. A spat comprising a ribbed body portion and instep and heel covering portions integral therewith, said instep and heel portions having at their exposed edges a continuous finishing stitch for adding elasticity to the material and to prevent the fraying thereof, and comprising extensions having rounded ends designed to extend completely over the instep and heel of the wearer. 35

2. A spat comprising a cylindrical body 40 of ribbed transversely elastic material having a front and a rear extension, said front extension being of greater length than said rear extension and the material of said body intermediate said sections being undercut, 45 an elastic edging stitched about the entire bottom of the garment, and an elastic foot engaging strap disposed upon said garment with its ends secured adjacent to said undercut portions of said body. 50

3. A spat as defined in claim 2 wherein 55 said cylindrical body is without openings at the sides thereof and is designed to be drawn over the foot after the fashion of a short hose.

ADOLPH L. FRIEDENTHAL.
